UNITED STATES PATENT OFFICE.

GEORGE W. SLACK, OF NORTHLVILLE, NEW YORK.

DESIGN FOR A LADDER-HOOK.

SPECIFICATION forming part of Design No. 28,489, dated April 19, 1898.

Application filed November 13, 1897. Serial No. 658,498. Term of patent 14 years.

To all whom it may concern:

Be it known that I, GEORGE W. SLACK, a citizen of the United States, residing at Northville, in the county of Fulton and State of New York, have invented and produced a new and original Design for Ladder-Hooks; and I do hereby declare the following to be a full, clear, and exact description of the same, reference being had to the accompanying drawing, forming a part thereof.

In the accompanying drawing the figure represents a perspective view of a ladder-hook embodying my new design.

As shown in the drawing, the leading or material feature of my design consists of a downwardly-curved body portion A, having an eye a at one end and a shoe or runner at the other end. At an intermediate point the

body portion is extended upwardly, then downwardly and slightly backward to form an engaging recess a', and is then carried forwardly and upwardly, as at a'', like a shoe or runner. At a point in rear of the recess a' is shown a slot a''.

Having now described my invention, what I claim as new, and desire to secure by Letters Patent, is—

The design for a ladder-hook as herein shown and described.

In testimony whereof I hereunto affix my signature in presence of two witnesses.

GEORGE W. SLACK.
